UNITED STATES PATENT OFFICE.

WILLIAM R. DUTEMPLE, OF PROVIDENCE, RHODE ISLAND.

DESIGN FOR A GEM-SETTING.

SPECIFICATION forming part of Design No. 15,064, dated June 17, 1884.

Application filed April 25, 1884. Term of patent 7 years.

To all whom it may concern:

Be it known that I, WILLIAM R. DUTEMPLE, a citizen of the United States, residing at Providence, in the county of Providence and State of Rhode Island, have invented and produced a new and original Design for Gem-Settings; and I do hereby declare the following to be a full, clear, and exact description of the invention, reference being had to the accompanying drawings, and to letters or figures of reference marked thereon, which form a part of this specification.

Figure 1 is a side elevation of my newly-designed setting as applied to a scarf-pin. Fig. 2 is a front view of the same with the gem or stone removed. Fig. 3 is a sectional view of the setting.

The leading feature of my design consists of two or more raised bands or corrugations extending around the outside surface of the setting.

My design further consists of a series of fine

V-shaped points on the upper edge of the top band, which gives a neat and finished appearance to the setting.

25

B is the setting complete.

a represents the raised bands, and a' the depressions, each extending continuously around the setting B.

a^2 represents the V-shaped points around the 30 edge of the top band.

What I claim as new is—

The design for a gem-setting herein shown and described, consisting of two or more raised bands, a , and depressions a' , the top band a 35 having a series of V-shaped points, a^2 , on its upper edge.

In testimony whereof I have affixed my signature in presence of two witnesses.

WM. R. DUTEMPLE.
